ELECTRIC SWITCH

Filed Oct. 4, 1928

Inventor
Rudolf Bigenwald,
by Charles E. Tullar
His Attorney.

UNITED STATES PATENT OFFICE.

RUDOLF BIGENWALD, OF HIRSCHGARTEN, GERMANY, ASSIGNOR TO GENERAL ELECTRIC COMPANY, A CORPORATION OF NEW YORK.

ELECTRIC SWITCH.

Application filed October 4, 1928, Serial No. 310,320, and in Germany November 17, 1927.

My invention relates to electric switches of the liquid break type and particularly to explosion chamber casings for such switches. Explosion chamber casings commonly have been constructed of metal with an insulation lining and with an insulating bushing in the bottom. It has been proposed to construct the explosion chamber casing in part of a strong insulating material, such for example as hard paper, but difficulties have been encountered in securing together the parts forming the complete casing. It is an object of my invention to provide an improved explosion chamber casing, constructed in part at least of insulating material having simple and effective means for securing together the various parts thereof.

My invention will be better understood from the following description taken in connection with the accompanying drawing, and its scope will be pointed out in the appended claims.

Referring to the drawing the single figure of which represents a fragmentary cross sectional view of a liquid break switch involving my invention, the enclosing vessel or tank 1 contains insulating liquid 2 in which the contacts are immersed. Supported by the insulator bushing 3 and connected with the contact stud 4 is the plate 5 forming the top of the explosion chamber casing in which is mounted the fixed contact 6. This contact is of the well known socket type which is adapted to receive the movable contact rod 7. In the complete switch two similar contact rods 7 are secured at opposite ends of the bridge 8, the two rods being associated with two similar explosion chamber casings in the common and well understood manner.

The cylindrical wall 10 and the bottom wall 11, of each explosion chamber casing are of insulating material such as hard paper. To facilitate firmly securing these two walls together and the cylindrical wall to the top plate 5, I construct the cylindrical wall with conical upper and lower portions, the upper portion flaring outwardly and the lower portion flaring inwardly. It will be understood that if the hard paper is impregnated with bakelite, the cylindrical wall will be deformed to produce the conical portions before the bakelite is cured. The upper plate 5 is provided with the internal flange 12 having a conical outer face and screw threaded to this plate is the clamping ring 13 having a conical inner face. By tightening this ring the wall 10 is firmly clamped to the top plate 5. The bottom plate 11 has a conical periphery corresponding with the lower conical portion of the cylindrical wall, thus firmly securing the bottom wall against being blown out by internal pressure. The throat bushing 15 is also of insulation and may be of hard paper like the walls 10 and 11. I have shown the bottom wall 11 with the material thereof arched inwardly thereby better to withstand the great pressure to which it is sometimes subjected. As a protection against the effects of an arc drawn between the contacts in the explosion chamber, I have shown the separate insulating cylinder 16 which member may be constructed of a material which while not necessarily having the strength of the wall 10 may be better adapted to withstand the effects of the arc and hot gases, and thus protect the wall 10. The separately formed members 10, 11 and 15 are preferably impregnated with bakelite or a similar material and after being assembled are cured, thus securely binding together the several parts.

While I have described only one embodiment of my invention, I do not wish to be limited to the particular form shown and described as it will be apparent that many modifications therein may be made without departing from the scope of my invention as set forth in the appended claims.

What I claim as new and desire to secure by Letters Patent of the United States is:

1. An explosion chamber casing for a liquid break switch comprising a cup-like insulating member having an outwardly inclined edge portion, a cover engaging the inner face of said inclined edge portion, and a clamping member cooperating with the cover and engaging the outer face of said inclined edge portion.

2. An explosion chamber casing for a liquid break switch comprising a cup-like insulating

member having a conical edge portion, a cover having a conical portion engaging the inner face of said edge portion, and a clamping member adjustably secured to the cover and

5 having a conical portion engaging the outer face of said edge portion.

3. An explosion chamber casing for a liquid break switch comprising a hollow cylindrical insulating member having an inwardly inclined end portion, and an insulating end plate therefor fitting within and retained by said inclined end portion.

4. An explosion chamber casing for a liquid break switch comprising a hollow cylindrical insulating member having an inwardly inclined conical end portion, and an insulating end plate therefor having a central contact opening and a conical periphery fitting within said conical end portion, said end plate

20 having an insulating bushing arranged in the opening therein.

5. An explosion chamber casing for a liquid break switch comprising a cylindrical member of hard paper having its upper and lower ends pressed to form respectively outwardly flaring and inwardly flaring conical portions, a metal cover therefor having a flange engaging the inner face of the outwardly flaring conical portion, a ring threaded to said cover and engaging the outer face of the outwardly flaring conical portion, an end plate of hard paper fitting within and retained by said inwardly flaring conical portion, and an insulating bushing secured in said end plate.

30 35 In witness whereof, I have hereunto set my hand this 18th day of September, 1928.

RUDOLF BIGENWALD.
